CIGARETTE MANUFACTURING MACHINE

Paul Johannes Herrmann, Dresden, Germany,
assignor, by mesne assignments, to J. C. Muller
N. V., Rotterdam, Netherlands

Application February 18, 1936, Serial No. 64,529
In Germany February 19, 1935

10 Claims. (Cl. 131—66)

This invention relates to cigarette manufacturing machines, and has for an important object thereof the provision of a machine of relatively small size which is capable of making a cigarette of uniform size and compactness.

In the machines at present available for making cigarettes the machines are relatively large in size in order to perform the various steps looking to the completion of the cigarette, and this bulkiness in the machines makes constant supervision impracticable for one person, and it is, therefore, an object of this invention to provide a relatively small, compact machine wherein the tobacco particles are fed to the rod-forming means at right angles to the movement of the rod-forming means so that the operator of the machine can readily watch the supply while at the same time being in a position to keep close supervision on the other operative parts of the machine.

Another object of this invention is to provide a tobacco spreader and selecting means wherein the heavier tobacco particles are removed and the lighter or acceptable particles are carried along to the rod-forming means.

A further object of this invention is to provide in conjunction with the rod-forming means a tobacco compacting device which will compress the tobacco particles and subsequently deliver the compressed rod to a shaping device where the rod is wrapped with the paper and an adhesive applied, the wrapped rod then being carried along to a cutting means where the desired lengths are cut off.

A still further object of this invention is to provide in a machine of this character means whereby the wrapper may be fed to the rod-forming means simultaneously with the feeding of the loose tobacco particles so as to facilitate the delivery of the compacted rod to the shaper.

With the foregoing and other objects in view, the invention will be more fully described hereinafter, and will be more particularly pointed out in the claims appended hereto.

In the drawings, wherein like symbols refer to like or corresponding parts throughout the several views:

Figure 1 is a detail side elevation of a machine constructed according to an embodiment of this invention.

Figure 1a shows the eccentric mounting of the bearing 30 for the compressing disc 26.

Figure 2 is a top plan of the machine.

Figure 3 is a sectional view taken on the line 3—3 of Fig. 2.

Figure 4 is a sectional view taken on the line 4—4 of Fig. 1.

Figure 5 is a fragmentary sectional view taken on the line 5—5 of Fig. 1.

5 Figure 6 is a view similar to Fig. 5 but showing a modified form of receiving trough.

Figure 7 is an enlarged fragmentary side elevation of the receiving trough and means for conveying the loose particles to the compressing device.

10 Figure 8 is a sectional view taken on the line 8—8 of Fig. 7.

Figure 9 is a view similar to Fig. 1, but showing a modified form of feeding device for the wrapper.

15 Referring to the drawings, wherein like symbols designate like parts throughout the several views, the numeral 1 designates generally a base upon which a frame 2 is mounted. The base 1 has a hopper or tobacco supply member 10 at

20 the rear thereof, and the bottom of this hopper 10 is closed by the upper run of an endless conveyor belt 40 which is mounted on rollers 41 and 42. A transfer drum or roller 11 is mounted on a shaft 43, and the conveyor 40 constantly moves

25 the tobacco in the direction of the drum 11 and the particles are carried upwardly and over the top of this drum 11 through rotation thereof. Rollers 12 and 13, which are mounted on shafts 44 and 45, are disposed in substantially contacting

30 relation to the drum or spreader 11 and serve as a means of providing a uniform delivery of tobacco particles by the spreader 11. A shield or scraper 46 engages the roller 12, and a similar shield or scraper 47 engages the roller 13 so as to prevent any of the tobacco particles from being carried around these rollers 12 and 13.

35 A rotating brush or cleaning member 14 is mounted at the discharge side of the spreader 11 below the roller 12, and this brush or cleaning member 14 discharges the particles of tobacco onto rotating blade structure 15 which is adapted to throw the loose particles forwardly and at a slight upward inclination, as shown in Figure 3.

The heavier particles are thrown with sufficient force to be delivered into a receiving chamber 16, as shown in Fig. 3, and the lighter and acceptable particles are delivered to a forwardly moving conveyor 17 which passes beneath a vertical wall 18

50 the front portion of which constitutes an abutment against which the lighter particles strike and fall downwardly onto the conveyor 17. Any metallic particles present in the tobacco as it travels on conveyor 17, are removed by magnet M 55 suitably supported adjacent the rear portion of

the vertical wall 18 and above the conveyor 17 as clearly shown in Fig. 3.

The conveyor 17 delivers the tobacco into an elongated and relatively narrow channel 20, the bottom of which is closed by the upper run of a conveyor 21 which travels at right angles to the movement of the conveyor 17. The front wall of the channel 20 is formed by the inner run of a conveyor 8 which moves in the same direction as the conveyor 21 and at substantially the same speed, and the inner wall of the channel 20 is formed by a stationary wall member 48, the upper end of which is beveled as at 49.

A beater or brush member 19 is rotatably mounted at the forward end of the conveyor 17 in a position whereby this beater or brush member 19 will throw the tobacco particles forwardly and downwardly into the channel 20 and at the same time remove all of the particles from the conveyor 17 at the forward end thereof. Through the provision of the conveyor 8 of the channel 20 the tobacco is not permitted to pile up and therefore form an uneven rod.

A stationary outer wall 50 extends from the forward end of the conveyor 8 and is disposed parallel with the inner wall 48, and these two wall members 48 and 50 extend to a point at substantially the bottom of a compressing means, including the members 24, 25 and 26. The tobacco carried along the channel 20 by the conveyor 21 is delivered to said compressing means, which are secured together by a pin 29. Said disks 24 and 25 are rotatably mounted on a stationary shaft 27 carried by the frame 2. An intermediate disc or plate 26 is disposed between the disks 24 and 25, and is smaller in diameter than the disks 24 and 25, so that the disks 24 and 25 constitute the sides of an annular groove 22 of which the disk 26 forms the bottom. The groove 22 is arranged so as to receive tobacco conveyed from the channel 20 by the conveyor 21. The side walls of the groove 22 and the belt 21 constitute a tobacco rod-forming means. Said disk 26 is carried along by means of said pin 29 when the disks 24 and 25 rotate, said pin 29 passing through a long slit-like radially placed aperture 32.

The inner disk 26, the periphery of which forms the bottom of the forming groove 22, is rotatably mounted on an eccentrically disposed member 30 which is secured to the stationary shaft 27, and this member 30 is preferably adjustable through a slot 31. The shallowest portion of the groove 22 is maintained at the top by means of said eccentrically disposed member 30, and in this manner the rod groove 22 is gradually reduced in the direction of the movement of the tobacco.

The conveyor 21 is continued about the periphery of the rod forming means, including the members 24, 25 and 26 for a distance of substantially one hundred and eighty degrees and the inner run of this conveyor constitutes one wall of the compressing means and holds the tobacco in the channel 22. A plurality of idler rollers 23 are disposed between the two runs of the conveyor and serve to maintain the two runs of the conveyor spaced apart. The forward end of the conveyor 21 extends in parallel relation to the channel 20 and engages a roller 23a and is spaced from a rod-removing member 33 which is supported by the frame of the machine and extends into the channel 22.

A channelled shaping member 35 is disposed forwardly of the releasing member 33, and the compressed rod removed from the compressing means, including the members 24, 25 and 26, is

forced through this shaping member 35 by reason of the rotation of the compressing means, including the members 24, 25, and 26 and the release of the rod from the channel 22 under the action of the releasing member 33.

The rod is adapted to be wrapped by paper or other suitable wrapper 5 fed from a supply roll 4 supported on a shaft 51 carried by the frame 2. The wrapper strip 5 is passed through a printing device 3 mounted in the frame 2, and on leaving the printing device, the strip is trained under an idler roller 52 and passes over a roller 36 disposed adjacent the releasing member 33 as shown in Fig. 1, so that the strip 5 will move with the rod 34 by means of a conveyor belt 53, into the shaper 35 where the strip 5 is wrapped about the rod 34 into the desired cylindrical shape.

While I have shown and described the wrapper being fed to the rod after the latter has been formed by the compressing means, the wrapper may be fed directly to the compressing means prior to the formation of the tobacco rod as shown in the modification illustrated in Fig. 9, whereby the tobacco is wrapped simultaneously with the formation of the tobacco rod. In this event, after leaving the printing device 3, the strip 5a is trained over the idler 52a adjacent the compressing means and enters the channel 22 ahead of the entrance thereto of the uncom-pressed tobacco.

After the wrapped rod leaves the shaper 35 it is conveyed by belt 53 to an appliance 37 which applies an adhesive to the wrapper or strip 5 or 5a, and from this adhesive applying device 37 the rod 34 moves along a guide member 9 in the form of an elongated channel which guides the rod 34 to a cutting device 38 where the wrapped and sealed rod 34 is cut up into the proper lengths to form the cigarettes.

Supplemental wrapper roll 6 is provided in the frame 2 so that a constant supply of the strip 5 or 5a may be assured. The cigarettes as they are cut off by the cutting device 38 are passed along to a table 39 from which point they may be readily removed for packaging.

In Figure 6 there is disclosed a modified form of receiving channel for the loose tobacco, and in this form the particles are carried along by the conveyor 17' and removed by the brush 19' which discharges the particles into the channel 20'. The channel 20' has an inclined forward wall 8' of the movable type, the channel 20' decreasing in width downwardly to the upper run of a movable bottom member 21', which is similar to the bottom member 21. The inner or rear wall 49' of the channel 20' is in this instance vertical.

In the use and operation of the machine illustrated in Figs. 1-4, the loose tobacco particles are deposited into the hopper or receiver 10, the bottom wall 40 of which moves forwardly in the direction of the rotating spreading member 11. The particles are carried over the top of this member 11, being evenly spread out by means of the rollers 13 and 12. The particles of tobacco fall downwardly on the side of this spreader 11 opposite from the hopper 10 and engage a brush 14 which directs the loose particles toward the projecting bladed member 15. The projecting member 15 rotates at such a speed as to cause the heavier particles to be thrown into the receiver 16, whereas the lighter and acceptable particles of tobacco fall downwardly on to the forwardly moving conveyor 17 and pass under the magnet M which removes any metallic particles

present in the tobacco. The conveyor 17 discharges the loose tobacco into the channel 20, the brush 19 facilitating the removal of the particles from the forward end of the conveyor 17. When the loose tobacco enters the channel 20, the conveyors 8 and 21 carry it along the channel 20 to rod-forming means including rotatable discs 24, 25 and 26 which form a rod channel 22. The loose particles are held in the channel 22 by the conveyor 21 which extends approximately 180° about the periphery of said discs from the bottom thereof to the top. The movable wall disc 26 of the rod-forming means being eccentrically mounted, gradually compresses the tobacco in the channel 22 until the top of the machine is reached, at which point the releasing member 33 will remove the compressed rod 34. After leaving the rod-forming means the tobacco rod 34 is delivered on to the wrapper strip 5 coming from the supply roller 4 and printing device 3, and both are conveyed by conveyor belt 53 through the shaper 35 where the strip 5 is wrapped about the tobacco rod and properly shaped, and both are then delivered to the adhesive applying means 37, which seals the wrapper strip 5 about the rod 34. From here, the wrapped and sealed rod is conveyed through the guiding channel 9 and into the cutting device 38, where the wrapped rod is cut into proper cigarette lengths and delivered to a table 39 from whence the cut cigarettes may be removed for packaging.

In the operation of the machine illustrated in Fig. 9, the strip 5a is fed to the channel 22 of the rod-forming means including the rotatable discs 24, 25 and 26, so that said strip is wrapped about the tobacco simultaneously with the formation of the rod instead of being applied after the formation of the rod, as disclosed in Fig. 1. From the rod-forming means, the wrapped rod is conducted to the shaper 35 where it is properly shaped and conveyed to the other stations of the apparatus, as above described in connection with machine of Fig. 1.

From the foregoing, it is believed that the construction, operation and advantages of the present invention will be readily understood by those skilled in the art, without further description, it being borne in mind that numerous changes may be made in the details disclosed without departing from the spirit of the invention as set out in the following claims.

What is claimed is:

1. A cigarette machine comprising a hopper, means for removing loose tobacco particles from the hopper, means for separating the heavier from the lighter particles removed from the hopper, a rotatable compressing member having a tobacco rod forming channel in the periphery thereof, means for delivering the loose particles to the channel of said compressing member, means for maintaining the loose particles in the channel of said compressing member during the rotation thereof, means for removing the compressed rod from the channel of said compressing member, means for wrapping a paper strip around the rod, means for applying an adhesive to the wrapped rod, and means for cutting the rod into cigarette length, the delivery means of the loose particles being substantially parallel with the rod-forming means and substantially perpendicularly below the same.

2. In a cigarette machine, the combination of means for feeding tobacco in one direction, means for forming said tobacco and a strip of paper into a cigarette rod, moving in the opposite di-

rection, means interposed between said two means for conveying the said tobacco from the feeding means to the rod-forming means, and a tobacco spreader for supplying said feeding means with tobacco, arranged below the rod-forming means.

3. In a cigarette machine, the combination of means for feeding tobacco in one direction, means for forming said tobacco and a strip of paper into a cigarette rod, moving in the opposite direction, means interposed between said two means for conveying the said tobacco from the feeding means to the rod-forming means, and a tobacco spreader for supplying said feeding means with tobacco, arranged below the rod-forming means, said interposed means comprising a conveyor disc, and said feeding means extending over said conveyor disc.

4. A cigarette machine comprising a tobacco spreader, a tobacco receiving channel member including a movable wall arranged at the end of said spreader, means for moving said movable wall during a portion of its travel through 180 degrees, a releasing member in the path of the tobacco on said movable wall, means for supplying paper to the tobacco, cigarette forming means for said tobacco and paper, said tobacco channel being substantially parallel with the cigarette forming means and substantially perpendicularly below said cigarette forming means, and means disposed between said channel and cigarette forming means and cooperating with said movable wall to form the tobacco into a rod.

5. A cigarette machine comprising a tobacco spreader, a tobacco receiving channel member including a movable wall arranged at the end of said spreader, means for moving said movable wall during a portion of its travel through 180 degrees, a releasing member in the path of the tobacco on said movable wall, means for supplying paper to the tobacco, cigarette forming means for said tobacco and paper, said tobacco channel being substantially parallel with the cigarette forming means and substantially perpendicularly below said cigarette forming means, and a conveyor means disposed between the tobacco channel and cigarette forming means and cooperating with said movable wall to form the tobacco into a rod and consisting of a shaft, spaced discs on said shaft, and a disc disposed between said spaced discs and of smaller diameter, so as to leave an open space at the periphery for receiving the tobacco.

6. A cigarette machine comprising a tobacco spreader, a tobacco receiving channel member including a movable wall arranged at the end of said spreader, means for moving said movable wall during a portion of its travel through 180 degrees, a releasing member in the path of the tobacco on said movable wall, means for supplying paper to the tobacco, cigarette forming means for said tobacco and paper, said tobacco channel being substantially parallel with the cigarette forming means, and substantially perpendicularly below said cigarette forming means, a conveyor means disposed between the tobacco channel and cigarette forming means and cooperating with said movable wall to form the tobacco into a rod and consisting of a shaft, spaced discs on said shaft, and a disc disposed between said spaced discs and of smaller diameter, so as to leave open space at the periphery for receiving the tobacco, said interposed disc being arranged eccentrically between said spaced discs, and means for moving said eccentric discs between the spaced discs, to gradually decrease the size of the peripheral

space from the point of reception of the tobacco on the conveyor means to the point of delivery of the tobacco by the conveyor means to the forming means.

7. A cigarette machine comprising a tobacco spreader, a tobacco receiving channel member including a movable wall arranged at the end of said spreader, means for moving said movable wall during a portion of its travel through 180 degrees and then in the opposite direction, a releasing member in the path of the tobacco on said movable wall, means for supplying paper to the tobacco, cigarette forming means for said tobacco and paper, said tobacco channel being substantially parallel with the cigarette forming means and substantially perpendicularly below said cigarette forming means, a conveyor means disposed between the tobacco channel and cigarette forming means and cooperating with said movable wall to form the tobacco into a rod and consisting of a shaft, spaced discs on said shaft, and a disc disposed between said spaced discs and of smaller diameter, so as to leave an open space at the periphery for receiving the tobacco, and means for gradually compressing the tobacco in the peripheral space of the conveyor means.

8. In a cigarette machine, spaced curved side

walls, an endless belt extending across the space outwardly of the side walls, means to guide the belt around a substantial part of the curved edges of the side walls, an eccentrically-mounted compressing member between the side walls and movable radially thereof toward and from the belt, and cigarette forming means for receiving the tobacco after being compressed by said member.

10. In a cigarette machine, tobacco feeding means, cigarette forming means positioned at a higher elevation than said feeding means, and rod forming means arranged between said feeding means and cigarette forming means and acting also as transfer means between the feeding means and the cigarette forming means, said rod forming means being curved from the feeding means to the cigarette forming means.

10. In a cigarette machine, tobacco feeding means, cigarette forming means, one said means being arranged at an elevation higher than the other means, and rod forming means curved from one means to the other, said feeding means and rod forming means having a common tobacco moving member extending substantially to the cigarette forming means.

PAUL JOHANNES HERRMANN.
